UNITED STATES PATENT AND TRADEMARK OFFICE
CERTIFICATE OF CORRECTION

PATENT NO. : Des. 506,214 S
APPLICATION NO. : 29/193734
DATED : June 14, 2005
INVENTOR(S) : Philip Zepter

Page 1 of 1

It is certified that error appears in the above-identified patent and that said Letters Patent is hereby corrected as shown below:

On the title page please delete item (73), the patent erroneously identifies an assignee as "Aracaria V.B., Amsterdam (NL)."

There has been no assignment and Philip Zepter is both the inventor and the owner.

Signed and Sealed this

Twenty-second Day of January, 2008

JON W. DUDAS
Director of the United States Patent and Trademark Office
